UNITED STATES PATENT OFFICE.

WILLIAM H. MILLS, OF BROOKLYN, NEW YORK.

IMPROVEMENT IN VENTILATING APPARATUS.

Specification forming part of Letters Patent No. **178,018**, dated May 30, 1876; application filed April 5, 1876.

To all whom it may concern:

Be it known that I, WILLIAM H. MILLS, of the city of Brooklyn and State of New York, have invented certain Improvements in Manner and Means for Ventilation of School and Audience Rooms, and dwellings, of which the following is a specification:

The object of the improvement is keeping a steady uniform passage of air through the room at an even pressure, with control of temperature, without dependence on opening windows, or exposure to drafts; also, to provide for the expulsion of the effluvia that exudes from human bodies, all of which does not ascend with the velocity of heated air, being more dense in its nature, continuing mixed with the air breathed longer than exhaled hydrogen.

The means employed consist in arrangement, adaptation, and combination of known devices—an air-pump, a receiving-reservoir, ingress and distributing-pipes, and openings for ingress and egress of the air to and from the rooms.

In the accompanying drawings the interior of a basement or cellar is shown, with the apparatus as arranged; also, the interior of a room, with provisions for ingress and egress of air.

A is the air-pump; B, the reservoir; C, the supply-pipe for the air-pump; D, the distributing-pipes; E, the air-entrance; F, an outlet, and G a fire-place under the reservoir. Stop-cocks *h* are placed where required;

the air-pump to work by hand or other power, as the size of the rooms require; the reservoir to be constructed so as to allow, as in a gasometer, a regulating control of the pressure of the air into the apartments or halls; the air to enter at the top with a pressure sufficient to cause an outflow near the floor to the outside of the building. A window lowered at the top, with an opening much smaller than the outlet at the floor, would, if needed, allow all the heated air to escape. The grosser or foul air would be kept down and be carried off with the artificial current induced by the pressure in the reservoir through the gratings near or in the floor. The supply-pipe reaches up through the partitions or walls into open air above the roofs of the buildings. The distributing-pipes are placed in the positions with openings where desired.

The air-entrances are proportioned to the area of the rooms or halls. The aerometer or reservoir can be used to purify the air by passing it through water, and can cool it by having ice on shelves in the interior; or in winter the air can be heated by the furnace beneath.

What I claim as my improvement is—

The combination of air-pump A, reservoir B, ingress-pipe C, and distributing-pipe D, in an apparatus for ventilation.

WILLIAM H. MILLS.
